CLAIM

I claim the ornamental design for a bar soap shaver, as shown and described.

DESCRIPTION

FIG. 1 is a top, front and left side perspective view of a bar soap shaver showing my new design.

FIG. 2 is a left side elevation view shown without the cap;

FIG. 3 is a right side elevation view thereof;

FIG. 4 is a front elevation view thereof;

FIG. 5 is a rear elevation view thereof;

FIG. 6 is a top view thereof; and,

FIG. 7 is the bottom view thereof.
